UNITED STATES PATENT OFFICE.

HENRY A. CARPENTER, OF SEWICKLEY, PENNSYLVANIA, AND DANA D. BARNUM, OF WORCESTER, MASSACHUSETTS, ASSIGNEES TO RITER-CONLEY MANUFACTURING COMPANY, OF PITTSBURGH, PENNSYLVANIA, A CORPORATION OF NEW JERSEY.

COAL-GAS-GENERATING APPARATUS.

1,122,683.

Specification of Letters Patent. Patented Dec. 29, 1914.

Original application filed July 24, 1913, Serial No. 780,996. Divided and this application filed September 17, 1914. Serial No. 862,188.

To all whom it may concern:

Be it known that we, HENRY A. CARPENTER, a resident of Sewickley, Allegheny county, Pennsylvania, and DANA D. BARNUM, a resident of Worcester, Worcester county, Massachusetts, citizens of the United States, have invented certain new and useful Improvements in Coal-Gas-Generating Apparatus, of which the following 10 is a specification, the same being a division of our application filed July 24, 1913, Serial No. 780,996.

In the manufacture of gas and coke by distilling coal in highly heated retorts, the 15 volatile matter is driven off in the form of gas, and this gas carries in suspension fine particles of ash and carbon which tend to lodge in the passages or conduits through which the gas is conducted from the retorts.

20 Continued or undisturbed accumulation of this deposit results in so contracting the passages as to materially retard the operation and decrease the efficiency of the apparatus. In addition to deposits of the char- 25 acter stated, condensation resulting from cooling produces deposit in the form of pitch, tar or light oils. Frequent and thorough cleaning of the passages is necessary to hold in check these obstructing and 30 stoppage-forming accumulations. The necessity for efficient cleaning is particularly present in those forms of apparatus in which a relatively large number of retorts are operated simultaneously for the pro- 35 duction of a relatively large volume of gas. In such apparatus the retorts are operated to best advantage by discharging and charging each retort at a different time interval from that of discharging and charging the 40 next adjacent retort or retorts, whereby the bench is maintained at substantially uniform and highly efficient distilling temperature regardless of the introduction of cold charges of fresh coal. If all the 45 retorts were discharged and charged simultaneously the operation would be intermittent, and the resulting wide variations of tem- 50 perature would seriously impair the retorts and other structural parts and would re- 55 sult in the production of gas varying in quality between the inception and the com- 60 pletion of the simultaneously preceding distillation of all the charges. By alternat-

ing the charging and discharging of the several retorts, and by segregating each 55 fresh charge from another fresh charge, a substantially even temperature of best effi- 60 ciency is maintained, the composite output of the retorts is of uniform quality, and the operation of the apparatus is continuous. 65 While no novelty is claimed herein for thus operating a gas bench which contains a relatively large number of retorts, such operation is referred to as emphasizing the importance of providing adequate means 70 for maintaining the gas passages fully open and clear of stoppage-forming deposits in order that the retorts and their outlets may operate uniformly and without interfering with the carefully prearranged time inter- 75 vals for discharging and charging.

Having in view the operating conditions thus briefly outlined, particularly as applied to generating apparatus of relatively large capacity, for instance a bench containing an upright succession of eight retorts discharging into the same standpipe, the primary object herein is to insure the maintenance of clean passages for the gas up to the point of its actual delivery into 80 the stand pipe. Ordinarily, the gas dis- 85 charges from each retort through a lateral passage or conduit which varies in length in different types of apparatus. Such pas- 90 sages are usually horizontal, or substan- 95 tially so, and afford the best opportunity for lodgment of the stoppage-forming deposits. They should, therefore, be readily accessible and if accumulation is to be prevented each passage must be cleaned from one extremity 100 to the other. And in order that such clean- 105 ing may be accomplished without appreciably interfering with the continuous operation above referred to, communication with the stand-pipe must be closed, with the entire length of the communicating passage accessible from the retort. To accomplish this, each passage is provided with a valve which is located at its stand-pipe extremity, so that with the valve closed the passage 100 may be cleaned from end to end. The valves are of course utilized for closing communi- 105 cation between stand-pipe and retorts when discharging and charging the latter, and the entire length of each passage may be cleaned as frequently as necessary during

these discharging and charging intervals. While it is necessary to keep down deposit accumulation in the stand-pipe, the present invention is not concerned with that problem, as heretofore indicated the primary purpose being to provide for free and unobstructed delivery of the gas from the retorts into the stand-pipe.

In the accompanying drawings, Figure 1 10 is an elevation of a portion of a bench or benches of gas retorts embodying the invention. Fig. 2 is a sectional elevation of the stand-pipe, retort mouth-pieces, and valved connecting passages. Fig. 3 is a sectional 15 plan taken on the broken line 3—3 of Fig. 2.

Referring to the drawings, 2 designates a gas bench, and 3 are the retorts, as here shown the latter being arranged one above the other in vertical succession. Two rows 20 of retorts may be arranged relatively close to each other as at the left hand of Fig. 1, with both rows served by the single stand-pipe or offtake 4, or a separate stand-pipe 4 may be provided for each row as at the right 25 hand of Fig. 1. Each retort is in separate communication with the stand-pipe through a lateral conduit 5 which is usually disposed horizontally, and its length depending upon the space intervening between the 30 retort and the stand-pipe, the latter being in effect a portion or continuation of the retort. When so formed the conduit consists of a lateral tubular extension of the mouth-piece 6, being located adjacent to the open end of 35 the latter which is closed by the usual door 7, here shown only conventionally. The outer extremity of the conduit-forming lateral extension of each mouth-piece is open to or through an upright wall of the stand- 40 pipe, as shown in Fig. 2, and provides a seat 8 for a valve 9, so that when this valve is closed the laterally extending conduit, which is open at its inner end through a vertical wall of the retort or mouth-piece, is fully 45 accessible through the latter for cleaning from end to end without appreciably interrupting the operation of the apparatus. The valve as here embodied opens inwardly, being carried by the crank arm 10 of an operating shaft 11, the latter extending to the exterior of the retort and provided with a suitable operating handle or lever 12. The valve and its operating means are of such 50 form as not to retard the conduit-cleaning 55 operation.

The particular embodiment of valve structure *per se* disclosed herein is the sole invention of Henry A. Carpenter, and is claimed in his application Serial No. 869,231, filed 60 October 29, 1914.

We claim:

1. The combination of a retort having a door closed opening, a stand-pipe, a gas con-

duit in communication with the stand-pipe and with the retort adjacent to its door-closed opening, and a valve for the conduit located to render the entire length of the conduit accessible from the retort for cleaning when the valve is closed. 65

2. The combination of a stand-pipe, a retort mouth-piece having a door-closed opening and an offset located inwardly from the door-closed opening and in communication with the stand-pipe, and a valve for the offset located to render the entire length of the 70 offset accessible from the mouth-piece for cleaning when the valve is closed.

3. The combination of a plurality of open-end gas retorts, a door for each retort, a stand-pipe, a laterally extending gas conduit 80 for each retort and at one end open thereto inwardly from its door-closed end, the opposite ends of the conduits open to the stand-pipe, and a valve for each conduit located at the stand-pipe end thereof 85 with the entire length of each conduit accessible from its retort for cleaning when the valve is closed.

4. The combination of a plurality of gas retorts, a mouth-piece for each retort forming an end continuation thereof, each mouth-piece having a door-closed opening and a conduit-forming offset located adjacent said opening, a stand-pipe, said conduit-forming offsets extending to and in communication 90 with the stand-pipe, and a valve for each offset located to render the entire length of such offset accessible through its mouth-piece for cleaning when the valve is closed. 95

5. The combination of a bench having a 100 series of retorts therein arranged horizontally at different elevations, mouth-pieces—one for each retort—projecting from the bench, each mouth-piece having a door-closed opening, a stand-pipe located at the 105 exterior of the bench, a series of laterally extending conduits—one for each mouth-piece, each conduit open at one end to its mouth-piece at a point adjacent the door-closed opening of the latter, the opposite ends of 110 the conduits separately open to the stand-pipe whereby the latter comprises an upright off take common to the series of retorts, and a valve for each conduit located at the stand-pipe end thereof whereby the 115 entire length of the conduit is accessible from its mouth-piece for cleaning when the valve is closed.
